COMBINED DRAWER FRONT, PULL, AND LABEL HOLDER

Robert J. Dottinger, Fairview, N.J., assignor to Cole Steel
Equipment Co., Inc., New York, N.Y., a corporation of
New York

Filed Sept. 15, 1965, Ser. No. 87,018

Term of patent 14 years

(Cl. D10—8)

FIG. 1 is a perspective view of a combined drawer front, pull, and label holder embodying my new design;

FIG. 2 is a left side view of the combined drawer front, pull, and label holder of FIG. 1;

FIG. 3 is a sectional view taken on line 3—3 of FIG. 1.

The broken line disclosure of a drawer body is shown for illustrative purposes only to illustrate environmental use.

I claim:

The ornamental design for a combined drawer front, pull, and label holder, as shown and described.
